BAG FRAME

George S. Merk, Flushing, N. Y.

Application September 4, 1940, Serial No. 355,324

1 Claim. (Cl. 150—29)

This invention relates to bag frames, and more particularly the hinged portion of the same.

The hinges of the bag frames heretofore proposed have the disadvantage that they readily separate from their pintles, during the course of manufacture of the frames, in consequence of which a factory putting out about 400 gross of frames a day, has a loss in frames of between thirty or forty thousand dollars per year in discarded frames. Furthermore, when the frames heretofore proposed are lined with bag material, this material enters between the frames, and thus causes upon the closing of the frames, injury to the hinges, and at the same time, a wearing of the bag material results.

The invention consists in the provision of a hinge axis in line with the meeting edges of the two parts of the frame, whereby the bag material is kept below the hinge line, and in the provision of ears struck out of the material of the frames, the axis of the hinge being also in line with that line coincident with the contacting surface of the two parts of the frame when in closed position, the flange of the ears being at right angles to the plane of the adjacent surfaces when the frame is closed. Another feature of the invention contemplates an improved form of fastening the parts of the frame together, so as to assure proper hinge action.

Structures embodying the proposed invention, have overcome the objections pointed out, and embodiments thereof will be shown in the accompanying drawing, described in the appended description and finally pointed out in the claim at the end of the description.

In the accompanying drawing:

Fig. 1 is a perspective view of an embodiment having my invention;

Fig. 2 is a detail plan fragmentary view;

Fig. 3 is a detail front fragmentary view;

Fig. 4 is a detail side fragmentary view;

Fig. 5 is a detail section of the hinge taken on line 5—5 of Fig. 3;

Fig. 6 is a plan view of the stamping from the initial blank;

Fig. 7 is a sectional view showing the preliminary shape to which the stamping is formed;

Fig. 8 is a sectional view showing the final shape to which the stamping is formed, and

Fig. 9 is a detail sectional view of the improved fastening device.

Similar characters of reference indicate corresponding parts.

Referring to the drawing, and more particularly to Fig. 6, in which the stamping 10 is shown,

this results from a strip of metal having been acted upon by male and female dies. These operate to cut out the length of one member of a frame, two of such members when hinged together constituting a bag frame. The configuration of these dies is such that each stamping 10, has two externally arranged ears 11 and 12, each separated from the remaining material of the stamping by curved cutouts 13 and 14. The ends of the stamping 10 are straight as shown by 15 and 16, and the lines passing through these edges pass through the centers of the holes 17 and 18 of the ears 11 and 12. The lines 19 and 20 indicate bend lines, which divide the stamping into the central horizontal part A, and the two vertical parts B and C when bent. Each vertical part or leg, B or C, has a projection 22, with a lug 23, and this lug engages an opening 24, when the stamping is shaped as shown in Fig. 1, whereby a locking action is provided, and spot or other welding is thereby avoided. Before the bending and locking actions just described, the stamping is bent transversely, as shown in Fig. 7, wherein the marginal portion 25 is bent at right angles, and as shown in Figure 8 wherein the other marginal portion 26 is double bent on the score lines 27 and 28. This forms the shape of the frame to enable the bag material to be inserted and clamping held in position. This stamping, as stamping, and this bending, as bending, forms no part of the present invention. The two important features of this stamping are the ears, with their curved cutouts and the locking action of the projections at the corners of the frame.

By the bending described, the ears 11 and 11a, take a position at right angles to the edges 15 and 15a, as seen in Fig. 2, the dot dash line d—d indicating this relationship. In Fig. 3, the flat surfaces 29 and 30 abut against each other in substantial surface contact, when the frame is closed. In Fig. 3, the dot dash line e—e indicative of the surfaces 29 and 30 of the frames also passes through the center of the hole of the ears. In Fig. 5, the dot dash line d¹—d² passes through the edge 16 and edge 16a and through the center of the hole 18 of the hinge. These ears are joined by a rivet 31, upset at both ends, as clearly seen in Figs. 4 and 5.

The relationship of the coincident lines and centers assures an ideal hinge action. The positioning of the rivet at right angles to the plane of the ears assures the greatest resistance to a pulling action. And the edges 15 and 15a, and 16 and 16a, constantly abutting, or substantially

abutting, prevent bag material from crowding between the surfaces 29 and 30, and thereby injuring the hinge action, or itself being injured.

It is known that two inverted U-shaped members hinged at the free ends of their legs, make up a frame for a handbag. It is also known to have U-shaped transverse sections to clamp the bag material. The difficulties attendant such hinges have now been obviated by the improved hinge of this invention.

The hinge has been shown in Figures 1 to 9 as being at the exterior part of the frame. It can be at the inner side as well, though the outer side location presents advantages over the inner side, as is known to one skilled in the art.

Referring again to Fig. 2, it will be noted that the exterior of one ear 12 is flush with the edge of the leg having the surface 29, whereas that of the ear 12a is slightly bent inwardly of the ear 12, as is shown by the bend 12c. Thereby the two ears have their surfaces flush with each other. At the other side of the frame as shown in Fig. 1, the respective ears are in reverse; at this side, the ear 11a is flush with the side surfaces 27a, while the ear 11 of the opposed leg is bent inwardly, as shown by the bend 11c, laterally inwards of the side surface 28. The curved cutouts 13 and 14 permit such bending. The axis of the pintle rivet 18 is at right angles to the planes 27a and 28a of the legs.

In contrast to a butt, strap or link hinge having sleeve-like members passing around the pintle, the hinge herein shown or described is in the nature of a gate hinge. By pulling a butt, strap or link hinge, the sleeves around the pintle are likely to open; but with the form of hinge as shown in the drawing, the ears cannot open, and the pintle must be sheared, which is a stress difficult to overcome.

The invention then, consists in having each flat surface of the frames provided with hinge ears at right angles to such surfaces, and joining the frames by the ears secured to each other by the pintles. Also, in bringing the surfaces to a meeting edge to prevent the bag material from entering between the surfaces, the surfaces have their meeting edges in line with the axes of the pintles of the ears. Finally, the invention in-

cludes an improved locking device to assure the ears in proper relationship with each other.

By locking the separate frame members, by means of the projection with its lug engaging the slot, the frame becomes substantially rigid, and preferably does not have a detrimental effect upon the hinges.

From the foregoing it is believed that the construction and advantages of the invention may be readily understood by those skilled in the art without further description, it being borne in mind that numerous changes may be made in the details disclosed without departing from the spirit of the invention as set out in the following claim.

What I claim is:

In a bag frame, a bag frame section having two leg portions and a common intermediate portion joining said leg portions, each of said portions being formed of a flat blank bent into shape to form at least two surfaces bent at right angles to each other, one to form the edge of the section and one to form an opposed side when faced with another section and a third surface bent to hold the bag material against said edge, said edge of the blank having its free ends shaped with parts of the contours of the ears and said opposed side with cutouts shaping the remaining parts of the contours of the ears, the plane of said ears when said two surfaces are bent at right angles to each other being at right angles to the opposed side surface from which they were partly cut out and flush with the surface which forms the edge, said ears having pintle openings, the end edges of the opposed side being transverse to the leg portion and in line with the centers of said openings of said ears, whereby when two sections are pivoted to each other by pintles passing through the openings of the ears, the transverse edges of the opposed surfaces substantially contact in all positions of the sections in respect to each other, said line of contact being in line with the axes of the pintles to prevent the interior bag lining from moving between the transverse edges, the exterior bag material being held away by the third surface and edge surface from said transverse edges.

GEORGE S. MERK.
